UNITED STATES PATENT OFFICE.

LESLIE D. YAGER, OF FORT WAYNE, INDIANA.

ATTACHMENT PLUG.

Application filed November 9, 1923. Serial No. 673,747.

To all whom it may concern:

Be it known that I, LESLIE D. YAGER, citizen of the United States, residing at Fort Wayne, in the county of Allen and State of Indiana, have invented certain new and useful Improvements in Attachment Plugs, of which the following is a specification.

This invention relates to the art of electrical connectors, and has particular reference to a device of this kind commonly known as an attachment plug.

The primary object of the invention is to provide a multi-way attachment plug of simple and durable form, and having the parts thereof arranged in a compact manner, whereby the device may meet with all of the requirements for a successful commercial use.

Another object of the invention is to provide a five-way attachment plug, by the use of which numerous translating devices may be quickly tapped into the circuit of an electric lamp associated with the plug.

Another object is to provide a particular improved organization of elements for providing a five way attachment plug that may be manufactured and assembled with comparative ease and at a low cost.

A still further object of the invention is to provide a construction of five-way attachment plug wherein provision is made for readily dismantling the same when required for purposes of perusal or repair of parts of the same.

With the above general objects in view, and others that will become apparent as the nature of the invention is better understood, the same consists in the novel form, combination, and arrangement of parts, herein-after more fully described, shown in the accompanying drawings, and claimed.

In the drawings, wherein like reference characters indicate corresponding parts throughout the several views:

Figure 1 is a side elevational view of an attachment plug constructed in accordance with the present invention.

Figure 2 is an end elevational view of the device shown in Figure 1 looking toward the lamp socket thereof.

Figure 3 is a view similar to Figure 2, looking toward the other or plug end of the device.

Figure 4 is a longitudinal sectional view, taken substantially upon the line 4-4 of Figure 2.

Figure 5 is a transverse sectional view, taken substantially upon the line 5-5 of Figure 1.

Figure 6 is a view similar to Figure 5, taken on the line 6-6 of Figure 1.

Figure 7 is a transverse sectional view, taken on the line 7-7 of Figure 1.

Figure 8 is a perspective view of one of the receptacle terminals and its attached conducting strip as the same appears before the ends of said conducting strip are bent.

Figure 9 is a view similar to Figure 8, of another of the receptacle terminals and its conducting strip.

Figure 10 is a perspective view of the insulating plate employed between the sections of the body of the plug.

Figure 11 is a developed perspective view illustrating the relationship of the receptacle terminals and their conducting strips in the assembled plugs.

Figure 12 is a fragmentary perspective view of the bolts which hold the sections of the plug assembled and forms the central contact of the lamp socket and plug member, and

Figure 13 is a longitudinal sectional view taken substantially upon the line 13-13 of Figure 2.

Referring more in detail to the drawings, the form of the invention shown includes a body member of insulating material formed in longitudinal half sections 5 and 5' that are arranged in end to end relation, and have an insulating plate 6 interposed therebetween. The body sections 5 and 5' have pairs of transverse recesses or grooves 7 and 8 respectively in the adjacent or inner ends thereof, and said sections are so related as to have the recesses of one of the same extend in a direction at right angles to those in the other section, the recesses or grooves 7 and 8 being extended to open at opposite sides of their respective sections so as to present a pair of openings in each side of

the rectangular body for reception of the jack of cooperating attachment plugs.

- The central portions of the grooves or recesses 7 are widened and arranged within 5 the widened portions thereof are receptacle terminals 9 that are double ended and preferably constructed of substantially C-shape from strips of sheet metal so as to form spring contacts for engagement with 10 the jacks of a cooperating attachment plug inserted in either end of the grooves 7 at opposite sides of the plug. In a like manner, the recesses or grooves 8 have their central portions widened for reception of a 15 pair of double ended receptacle terminals 10 similar to the terminals 9, whereby the jacks of a cooperating attachment plug may be inserted in either of the remaining two sides of the plug body for cooperation with 20 said terminals 10. It will thus be noted that the pairs of contacts 9 and 10 cross each other and are insulated from each other by means of the disc 6 interposed between the adjacent ends of the body sections 5 and 5' 25 as clearly shown in Figures 1, 4, and 13.

At one end of the body of the plug is a lamp socket composed of an outer shell or sleeve 11 of insulating material within which is suitably rigidly secured the 30 threaded conducting shell or socket member 12 into which the base of an electric lamp is adapted to be threaded in a well known manner, the outer ends of the insulating tube or cylinder 11 being externally threaded as at 13 for detachable engagement with a shade or the like if it is desired to employ one in conjunction with the lamp engaged with the lamp socket.

- Positioned at the other end of the body is 40 a plug member including a core 14 of insulating material that is fitted within a threaded conducting shell 15 adapted to be screwed into the threaded socket of a fixture. The sections of the body are firmly 45 clamped together against opposite sides of the disc 6, and the lamp socket and screw plug are similarly rigidly secured against the opposite ends of the body by means of a relatively long bolt or screw 16 that is arranged axially of the plug and extends 50 through aligned openings in the bottoms of the shells 12 and 15 and through aligned openings in the body sections 5 and 5' and in the core 14 of the threaded plug. Arranged 55 between the head of the bolt 16 and the bottom of the shell 12 is a disc 17 of insulating material, and between the head of the bolt 16 and the disc 17 is one end of a resilient central contact 18 of the lamp 60 socket, the bolt 16 passing through said end of the contact 18 and the outer end of the latter overlying the head of the bolt 16 as shown clearly in Figure 4. Thus, the shell 12 forms the outer contact of the lamp socket, while the contact 18 is the central

contact thereof, and as the bolt 16 extends through the core 14 of the threaded plug, said bolt forms the central contact of said threaded plug. A nut 19 is threaded upon the end of the bolt 16 that projects through 70 the core 14, so as to tightly detachably maintain the parts in assembled relation.

One of each of the pairs of contacts 9 and 10 has a conducting strip 20 rigid therewith and these two conducting strips extend entirely through aligned passages in the body sections 5 and 5' terminating in inturned opposite ends 21 respectively flatly engaging the inner surfaces of the bottom walls of the shells 12 and 15. In this way, provision is 80 made for conducting the current from the shell 15 or outer contact of the screw plug to one receptacle terminal of each pair and also to the shells 12 for outer contact of the lamp socket. 85

The remaining receptacle terminal of one pair has a conducting strip 22 rigid with the central portion thereof that extends through a passage in the body section 5 and terminates in an inturned end 23 having an 90 opening 24, through which the bolt 16 passes, the bolt fitting in said opening 24 sufficiently tight to provide electrical connection between the strip 22 and the bolt 16. A disc 25 of insulating material is disposed 95 on the shank of the bolt 16 between the adjacent inturned ends 21 of the strip 20 and the inturned ends 23 of the conducting strip 22, so that current may not flow from the shell 12 to the conducting strip 22 and so 100 that current may not flow from the central contact or the bolt 16 to the conducting strip 20.

The remaining receptacle terminal of the other pair has a conducting strip 26 rigid 105 with the central portion thereof and extended through a passage in the body section 5' with its outer end inturned as at 27 and formed with an opening 28 through which the shank of the bolt 16 passes. An 110 insulating disc 29 is disposed between the end 27 of the strip 26 and the adjacent inturned end 21 of the strip 20, so as to insulate them from each other and to particularly insulate the end 27 from the base of 115 the shell 15, the opening 28 being sufficiently small to provide for electrical connection at this point between the strip 26 and the bolt 16.

It will thus be seen that electrical connection is provided between the outer contacts of both the lamp socket and the screw plug and one receptacle terminal of each pair, while similar connection is provided between the central contact of both the lamp socket and screw plug and the remaining receptacle terminal of each pair, whereby the jacks of a cooperating attachment plug may be engaged with the end of either pair of receptacle terminals to supply current to any de- 120

sired form of translating device, while a lamp is employed in the lamp socket. In other words, an attachment plug may be engaged with the receptacle terminal at all 5 four sides of the device for simultaneous use if desired, at which time a lamp may be employed within the socket shell 12 if so desired. While the strips 20, 22 and 26 are shown as separate pieces of metal riveted as 10 at 30 to the receptacle terminals 9 and 10, it is obvious that the same may be stamped from sheet metal integral with said terminal.

As shown in Figure 12, the bolt 16, may be formed with burrs on opposite sides of the 15 shank thereof, adjacent its head, so that when the bolt is forced through the opening 24 of the strip 22, said burrs will bite into the strip 22 for obtaining better electrical connection and to restrain the bolt 16 against 20 turning when it is desired to remove the nut 19 in dismantling the device, or holding the said bolt against turning when threading the nut 19 in assembling of the device.

In the operation of the device, we will 25 assume that the threaded plug including the shell 15 is screwed into the threaded socket of a fixture. When this is done, the adjacent end of the screw 16 will engage the central contact of said fixture socket while the 30 shell 15 will engage the outer contact or shell of said socket. Assuming that the current flows from the central contact of the fixture socket, it will pass through the screw 15 to both of the strips 22 and 26 and thence 35 to one of each of the pairs of receptacle terminals 9 and 10, which are respectively attached or connected with said strips 22 and 26. The current will also flow to the central contact 18 of the lamp socket, so 40 that, should a lamp be threaded in said socket the current will flow to the central contact of the lamp through the filament and then to the outer contact of the lamp. From the outer contact of the lamp, the current will flow through the shell 12 and strips 45 20 to the shell 15 and then through the outer contact or shell of the fixture socket. Should the jack of a cooperating attachment plug be inserted in the grooves 7 at 50 either of the two sides of the device, through which said grooves 7 open, the current will flow from the receptacle terminal 9 to which the strip 22 is attached to one of said jacks and return from the other jack to the other 55 receptacle terminal 9 to which one of the strips 20 is attached. In a like manner, should the jack of a cooperating attachment plug be inserted in the adjacent ends of the grooves 8 at either of the remaining two 60 sides of the device, the current will flow from the receptacle terminal 10 of the other pair to one of said jacks and return from the other jack to the other receptacle terminal 10 to which the other strip 20 is attached. 65 Thus, the jacks of as many as four cooper-

ating attachment plugs may be simultaneously attached with the present attachment plug for simultaneously supplying current to four individual translating devices, one of which is connected with the jacks of each 70 of said cooperating attachment plugs. It will also be noted that a lamp may be employed in the socket including the shell 12, simultaneously with the use of said cooperating attachment plug or independently 75 thereof and vice versa.

In order to prevent turning of the contact shells 12 and 15 relative to the body sections 5 and 5' and in order to obtain better electrical connections between said 80 shells 12 and 15 and the conducting strip 20, tongues 32 are stamped from the bottom of said shell in proper position to project into the passages through which the strips 20 extend as shown clearly in Figure 85 13.

As shown in Figure 10, the insulating plate 6 is provided with plugs or openings 33 and 34, the openings 33 being provided in position to permit passage of strip 20 90 therethrough and the slots 34 being provided to permit passage of the screws 16.

From the above description, it is believed that the construction and operation, as well as the advantages of the present device 95 will be readily understood and appreciated by those skilled in the art.

Minor changes may be made without departing from the spirit and scope of the 100 invention as claimed.

What I claim as new is:

1. In a multi-way attachment plug, a body of insulating material having a threaded lamp socket and a threaded plug respectively positioned at opposite ends 105 thereof, said socket and plug having central and outer contacts, two crossed pairs of receptacle terminals within the body, the receptacle terminals of each pair being double-ended for engagement of jacks of 110 a cooperating attaching plug at either of two opposed sides of the body, a pair of conducting strips extending through the body and each attached to one receptacle terminal of each of said pairs, a bolt extending through the body and electrically connecting the central contacts of the socket and plug, and additional conducting strips extending into the body and electrically connecting said central contacts with the remaining receptacle terminal of each pair, said first named conducting strips affording the electrical connection between the outer contact of the plug and socket respectively. 115

2. In a multi-way attachment plug, a body of insulating material having a threaded lamp socket and a threaded plug respectively positioned at opposite ends thereof, said socket and plug having central and outer contacts, two crossed pairs of 120

receptacle terminals within the body, the receptacle terminals of each pair being double-ended for engagement of jacks of a cooperating attaching plug at either of two opposed sides of the body, a pair of conducting strips extending through the body and each attached to one receptacle terminal of each of said pairs, a bolt extending through the body and electrically connecting the central contacts of the socket and plug, additional conducting strips extending into the body and electrically connecting said central contacts with the remaining receptacle terminal of each pair, said first named conducting strips affording the electrical connection between the outer contact of the plug and socket respectively, said body being formed of longitudinal half-sections and having transverse pairs of parallel spaced cross grooves in the adjacent ends thereof in which the aforesaid receptacle terminals are arranged, an insulating disc arranged between the adjacent ends of the body section and insulating the pairs of receptacle terminals from each other, said bolt being associated with the socket and plug in a manner to connect these parts to the opposite ends of said body.

In testimony whereof I affix my signature.

LESLIE D. YAGER.
